UNITED STATES PATENT OFFICE.

EDWARD F. HANKIN, OF PHILADELPHIA, PENNSYLVANIA.

ELECTRIC ETCHING INSTRUMENT.

1,387,394.

Specification of Letters Patent.

Patented Aug. 9, 1921.

Application filed August 23, 1920. Serial No. 405,346.

To all whom it may concern:

Be it known that I, EDWARD F. HANKIN, a citizen of the United States, residing at Philadelphia, in the county of Philadelphia and State of Pennsylvania, have invented 5 certain new and useful Improvements in Electric Etching Instruments, of which the following is a specification.

One object of my invention is to provide 10 an improved instrument which can be used in the manner of a pencil to write upon or otherwise mark metal so that the writing or marking will be actually etched by heat caused by a rapid succession of electric arcs.

15 Another object is to so construct my improved instrument that it can be freely and quickly moved by the hand and will therefore be an improvement over instruments previously made for said purpose and which 20 often stick due to irregularities in the contact and depth of marking.

A still further object is to provide an instrument which will produce the etching in such manner that it will be even and more 25 distinct than heretofore possible and so deep that it cannot be readily obliterated.

These objects, and other advantageous ends which will be described hereinafter, I attain in the following manner, reference 30 being had to the accompanying drawings in which—

Figure 1 is a top plan view of an electric etching instrument made in accordance with my present invention, and

35 Fig. 2 is a longitudinal section taken centrally on Fig. 1 and showing certain of the innermost parts in outside view.

Referring to the drawings, 3 represents a brass tube which is screwed at one end into 40 a head 4. This head 4 may be made of brass and includes two annularly projecting flanges 5 and 6 so as to provide a spool portion upon which is wound a number of wrappings of insulated electric conduit wire 7. The head 45 4 has a chamber 8 immediately to the rear of the tube 3 and in this chamber slides a core 9 preferably of soft iron; said core being connected to a rod 10 which is preferably made of brass. The rod 10 is slidably 50 mounted within the tube 3 and at its outer end, which projects beyond the outer end of the tube 3, is provided with a copper etching member 11 hereinafter termed a "point". This etching point may be screwed or other- 55 wise secured upon the rod 10 so that it may be removed and the etching point has a coni-

cal portion 12 for a purpose hereinafter described. A cap 13 has a portion 14 which is screwed within the end of the chamber 8 opposed to the core 9 and a coiled spring 15 is 60 interposed between the core 9 and the portion 14 of the cap 13 and serves to normally move the core 9 and rod 10 forwardly or in other words into the position shown in Fig. 2 with a part of the core 9 located forwardly 65 of the wire coil 7. The wire of the coil 7 may be either enameled or insulated in any other suitable manner and one end of this coil is grounded upon the head 4. The other end 16 of the wire of the coil is secured to a 70 binding post 17 as shown and a feed wire 18 is also connected to the binding post by means of a thumb screw 19. This feed wire may lead from one pole of an electric generator or other source of current and the 75 other pole of said generator will be grounded upon the metal which is to be etched.

The tube 3 is covered by an outer insulating sleeve 20. The binding post 17 extends through a band 21 of insulating material 80 which surrounds the forward portion of the head 4. A clamp 22 is secured on the forward end of the sleeve 20 and is split at one side so as to support an adjustable guide shoe 23; said guide shoe having an upwardly 85 curved portion 24 directly under the conical end 12 of the etching point 11 and I preferably make the extreme end of the curved portion 24 of the shoe globular or enlarged as illustrated.

90 In the use of my invention the instrument is held in the same manner as a pencil and considering that a plate of metal is to be etched either by writing or other marking, the curved portion 24 of the guide shoe 23 95 is moved into contact with the plate and afterward the instrument is swung on the portion 24 as a fulcrum or bearing until the extreme end of the conical portion 14 of the etching point engages the surface of the 100 plate to be etched. This will complete an electric circuit through the coil 7 and will cause the core 9 to be drawn into the field or zone of the windings of the coil 7 in the same manner as a solenoid. This movement of the 105 core will cause the rod 10 to be moved and the etching point to be raised from the plate. In so doing an electric arc or flame will be produced which will locally melt the upper portion of the plate. However, as soon as 110 the point 11 has been lifted from the plate due to the action of the solenoid coil 7, the

circuit will be broken and the spring 15 will then act to move the etching point 11 again into engagement with the plate and the action will be repeated.

- 5 In actual practice and use of my above described instrument I have found that this action is extremely rapid and during the solenoid action the instrument can be moved in the manner of a pencil over the plate and 10 any writing or other marking can be freely and quickly etched upon the plate and there is no possibility of the instrument sticking due to the contact or depth of marking. A distinct marking can be made of such depth 15 that it cannot readily be obliterated and any kind of metal which will conduct electricity can be readily etched by my improved instrument.

By having the enlarged or globular end 20 on the guide shoe 23, a smooth contact can be made with the article which is to be etched up to the time in which the etching point engages said article and in this manner the instrument can be freely and easily used for 25 writing purposes without undue friction between the shoe and the article which is to be etched.

While I have described my invention as taking a particular form, it will be understood 30 that the various parts of my invention may be changed without departing from the spirit thereof, and hence I do not limit myself to the precise construction set forth, but consider that I am at liberty to make such 35 changes and alterations as fairly come within the scope of the appended claims.

Having thus described my invention, what I claim as new and desire to secure by Letters Patent is:—

- 40 1. An etching instrument of the character described including an etching point and a solenoid operative to move said point out of electric contact with material to be etched; substantially as described.
- 45 2. An etching instrument of the character described including a head having a chamber; a core slidable within said chamber; an electric conduit wire coil on said head surrounding said chamber; a spring for 50 moving said core in a direction away from the field of said coil; and an etching point connected to said core and movable into engagement with an article to be etched whereby an electric circuit is completed 55 through the point and said coil, and said coil is operative to move the core and there-

by withdraw the etching point from said article to break the circuit; substantially as described.

3. An etching instrument of the character 60 described including a head having a chamber; a core slidable within said chamber; a tube connected to said head; a rod slidably fitting said tube and connected to said core and etching point on said rod and located 65 outside of said tube; an electric conduit coil surrounding said head and said chamber; a spring for moving said core in a direction out of the field of said coil, said coil having one end grounded upon said head; and 70 means for connection of the other end of said coil with one pole of an electric generator, said core, rod and etching point forming an electric conduit in connection with said head whereby when the other pole 75 of said generator is grounded on the article to be etched and the etching point is brought in contact with said article, the coil will be energized to draw said core into its field and the etching point will be moved away from 80 the article to cause an arc and the consequent etching of the article, said spring being operative to again move the etching point into engagement with said article; substantially as described. 85

4. An etching instrument including a supporting structure; an etching point supported by said structure; and a guide shoe insulated from said etching point and adjustable into various positions relatively to 90 said etching point; substantially as described.

5. An etching instrument including a supporting structure; an etching point supported by said structure; and a guide shoe 95 insulated from said etching point, said guide shoe having a portion curved toward said etching point; substantially as described.

6. An etching instrument including a supporting structure; an etching point supported by said structure; and a guide shoe 100 insulated from said etching point, said guide shoe having an enlarged curved portion located adjacent said etching point; substantially as described. 105

In testimony whereof I have signed my name to this specification in the presence of two subscribing witnesses.

EDWARD F. HANKIN.
